FIG. 1 is a perspective view of a fiber glass reinforced polyester housing structure showing my new design;

FIG. 2 is a top plan view thereof;

FIG. 3 is a front elevation thereof;

FIG. 4 is a left side view thereof;

FIG. 5 is a rear view thereof;

FIG. 6 is a right side view thereof;

FIG. 7 is a cross-section view thereof taken along line 7-7 of FIG. 6;

FIG. 8 is a perspective view of a modified form of the design shown in FIG. 1;

FIG. 9 is a top plan view thereof;

FIG. 10 is a front view thereof;

FIG. 11 is a left side view thereof;

FIG. 12 is a rear view thereof;

FIG. 13 is a right side view thereof;

FIG. 14 is a cross-section view thereof taken along line 14-14 of FIG. 13.

I claim:

The ornamental design for a fiber glass reinforced polyester housing structure, as shown and described.
